UNITED STATES PATENT OFFICE.

LOUIS BLOCK, OF NEW YORK, N. Y., ASSIGNOR TO LEAH ELIZABETH BLOCK, OF NEW YORK, N. Y.

COMMODE-DISINFECTANT.

1,049,559.

Specification of Letters Patent.

Patented Jan. 7, 1913.

Application filed March 13, 1912. Serial No. 683,635.

To all whom it may concern:

Be it known that I, LOUIS BLOCK, a citizen of the United States, and a resident of New York city, in the county and State of New York, have invented certain new and useful Improvements in Commode-Disinfectants, of which the following is a specification.

This invention relates to toilet disinfectors, and has for its primary object the provision of a simple, efficient and economical means for supplying an anti-septic or deodorant to commodes and the like. I provide a tubular body and attach it to the underside of the seat of the commode or toilet and provide it with means whereby it will supply the anti-septic or deodorant to the bowl in small quantity, as by dropping it in from time to time at one or more places, and I also provide means whereby the tube may be refilled with the compound used without removing the tube from the seat; and I also provide means whereby the amount of the compound delivered to the bowl may be varied.

The invention consists of features of construction and combinations of parts herein-after described and more particularly pointed out in the claims concluding this specification.

One embodiment of the invention is illustrated in the accompanying drawings, forming part hereof, in which—

Figure 1 is a view from beneath of the seat and the holder attached thereto; Fig. 2 is a detail of one form of dripper; and Fig. 3 is a detail of the holder.

The reference symbol 5 designates the seat of the commode, which is hinged as usual at the end marked 6 so as to be liftable as and when desired.

7 marks the usual rubber feet for resting on the top of the bowl to support the seat when it is down, and 8 marks the opening in the seat. To the underside of the seat and adjacent to the edge of the hole 8, I attach a bent tubular body 9 by cleats 10 or other suitable means. This body may be made in sections united to each other at 19, and I plug the ends by screw-stoppers 11 after introducing the wick 12, where I use the wick, and before filling at all times.

13 marks screw-caps for closing the filling-nipples near the front of the seat, and 14 marks the drip-tube of the device, which

drip-tube screws into the head 15 and has its 55 end closed by the adjustable screw-cap 16. The tube 14 is slotted at 17 to provide for the escape of the disinfectant and the size of the opening may be varied by screwing the cap 16 farther on or off. The tube 14 60 communicates with the tube 9, as will be understood. In order to prevent liquid disinfectant from running back on the seat or holder when the seat is tilted up, I provide a cup or catch 18 on the head 15. If desirable, the tube 9 may be perforated at its underside, as at 20, to permit the disinfectant to escape at points other than the slot 17.

It will be seen that I provide a simple 70 device for the purpose, a device which is hidden from view, which has no pipes to break or to be in the way or to clog, and which is yet readily accessible for refilling and which is always in place for performing 75 its work.

I claim—

1. The combination with a commode-seat, of a gravity-feed U-shaped disinfectant-holding vessel having its arms disposed at 80 opposite sides of the seat opening and consisting of a continuous tube provided with an adjustable outlet for the disinfectant.

2. The combination with a commode-seat, of a U-shaped vessel having its arms at 85 opposite sides of the seat-opening and consisting of a continuous closed tube having an outlet stub-tube provided with a slot through the wall thereof, and an adjustable slot-closer engaging said stub-tube and by 90 its adjustments varying the working area of said slot.

3. The combination with a commode-seat, of a U-shaped vessel having its arms at 95 opposite sides of the seat-opening and consisting of a closed continuous tube having an outlet stub-tube provided with a longitudinal slot through the wall thereof, and a cap adjustable along said stub-tube and closing said slot as desired.

Signed at New York city in the county of New York and State of New York this 8th day of March A. D. 1912.

LOUIS BLOCK.
